Attorney

UNITED STATES PATENT OFFICE

ALBERT F. FIFIELD, OF ST. CATHARINES, ONTARIO, CANADA, ASSIGNOR TO THE AMERICAN FORGE & HOE COMPANY, OF CLEVELAND, OHIO, A CORPORATION OF OHIO

RAIL ANCHOR

Application filed January 28, 1929. Serial No. 335,451.

My invention relates to rail anchors and relates particularly to the type of rail anchors attachable to railroad rails to prevent longitudinal movement thereof, and which are 5 made in only one piece.

One-piece rail anchors, so-called, are well known, but so far as I am aware, they are generally subject to certain disadvantages, some of which are possessed also by rail 10 anchors involving more than one part.

Among these a principal disadvantage is that a rail anchor must be made particularly for rails of a certain size and when, for instance, it is desired to use them on rails of 15 a different size this may not be done without reforming of the rail anchor, the reforming being generally more expensive than the cost of new anchors.

Many of the prior one-piece rail anchors 20 do not engage, by a sufficient surface thereof, with the fixed part of the railway road bed, such as a railway tie, to prevent movement of the anchor with the rail, or to prevent such undue pressures being exerted against the 25 tie as to wear it away in the portions contacting.

Among other disadvantages of prior rail anchors, are the difficulties of attaching and detaching from the rails.

30 An object of my present invention, therefore, is to provide an improved rail anchor of the one-piece type, adapted for use upon rails of different sizes.

Another object of my invention is to provide 35 an improved rail anchor of the one-piece type, adapted to present a very broad surface for engagement with the lateral surface of a rail supporting tie, which prevents movement of the anchor with the rail transversely of the tie, also to effect such engagement as will be most efficacious.

Another object of my invention is to provide 45 a one-piece rail anchor invertible to adapt it to different sized rails, providing in either position, a large tie engaging surface and adapted to adhere to the rail base by cooperating jaws engaging the fillet between the rail web, rail base and rail flange edge, respectively.

50 Another object of my invention is to pro-

vide an improved rail anchor which is readily and rigidly secured to a rail adjacent to a tie and readily removable therefrom.

Another object of my invention is to secure a plurality of the aforesaid objects in a single 55 anchor construction.

Another object of my invention is to provide a rail anchor adaptable for attachment to rails of a plurality of sizes, and which will be rigidly held thereon after attachment, 60 even though the rails of a given size may vary slightly in width of the rail bases, due to manufacturing tolerances.

Other objects of my invention and the invention itself will become apparent by reference to the following description of an embodiment of my invention, and in which description reference will be had to the accompanying drawings illustrating the said embodiment.

70 Referring to the drawings:

Fig. 1 is a side elevational view of an anchor embodying my invention attached to a rail of a given size illustrated in transverse section.

75 Fig. 2 is a plan view of the anchor of Fig. 1.

Referring now to the different figures of the drawing, in all of which like parts are designated by like reference characters, at 1 80 I show a rail having opposite lateral flanges 2 and 3, and a web 4 and fillets 5 intermediate the lateral surfaces of the web and the upper surfaces of the flanges. A rail tie is shown at 6, the rail being supported on the 85 tie extending transversely of a plurality of such ties, in the usual manner, spikes holding the rails to the tie by their heads superposed over the border portions of the rail flanges 2 and 3, in arrangement with the flanges.

90 The rail anchor of my invention is of the type adapted to be resiliently clamped to the rail base and abuttingly engage by a lateral surface the rail tie 6. The anchor, per se, as 95 illustrated in Figs. 1 and 2, and comprises an integral forging of steel or like resilient material, and is generally of E-form with an elongated intermediate tongue shown at 7 with flanged end 8.

100 From the head 9 of the anchor, the diverg-

ent arms 10 and 11 extend toward the flanged end 8 of the tongue 7, each being curved inwardly toward its end portion toward the tongue to form with the tongue a pair of 5 similar hooks.

5 The enlarged flanged head 8 is provided at each side with a pair of shoulders 12 and 13 and 12' and 13', arranged in stepped relation, a pair of the shoulders, such as 13 and 10 13', being disposed more remote from the head of the anchor than are the shoulders 12 and 12', so that a wider rail base corresponding in form to the rail base 1 may be receivable successively between the shoulders 15 13'-12' and the rail fillet engaging surface 14' of the arm 11, than the rail base 1, which is resiliently held between the fillet engaging surface 14 of the anchor arm 10 and the shoulders 12-13.

20 In the anchor of my invention, whichever one of the arms 10 or 11 engages by its fillet engaging surface 14 or 14' with the fillet inter-connecting the web and rail base, the other arm, such as the arm 11, Fig. 1, is disposed lowermost for engaging by its lateral surface with the abutting lateral surface of 25 the tie 6.

I prefer to employ a pair of shoulders such as 12-13 and 12'-13' for each of the duplex 30 retaining flanges 15 respectively, of the flanged end 8 of the anchor tongue 7, for convenience in applying the anchor to the rail base, although one of the shoulders, such as the shoulder 13 or 13', could be dispensed 35 with.

With the two shoulders provided, however, a workman applying the anchor to the rail, will hook the arm 10 over the rail base flange 2, and preliminarily will drive the 40 anchor by its head 9 to project the flanged end 8 laterally of the rail so that the first shoulder 13 or 13' will snap over the bottom edge 17 of the rail base.

After such a preliminary adjustment, a 45 sharp blow directed against the head 9 at approximately the position indicated by the arrow 18, will, by virtue of the resiliency of the arm 10, project the flanged head 8 sufficiently beyond the adjacent lateral surface of 50 the rail flange as to effect a snapping of the shoulder 12 over the rail base lower edge 17. The operation is the same when the anchor is reversed to apply it to a larger size rail base.

55 In applying the anchor to the rail, the fillet engaging surface 14 or 14', as the case may be, of the arms 10 or 11, respectively, will ride upwardly on the fillet as driving of the anchor on the rail base progresses.

60 A wedging effect is had as well as a final slight flexure of the arm 10 in the more vertically extending portion thereof, the combined flexing effects being efficacious in securing a very tight grip upon the rail base by 65 the anchor.

The idle pendant arm 10 or 11, as the case may be, presents a very broad tie engaging lateral surface so that gouging of the ties is reduced to a negligible amount and the ties are, therefore, enabled to more unyieldingly 70 resist movement of the anchors laterally by longitudinally directed efforts of the rail.

The arms 10 and 11 are preferably widened at 15 in order to effect a broad surface engagement at 14, and also to effect engagement by one of the lateral surfaces 16 of the flattened arm, with the rail tie 6, so as to tend to effect a sluing and canting action on the anchor on transverse and vertical axes, comprising respectively the longitudinal axis of 75 the tongue 7 and an axis extending vertically within the rail engaging surface 12 of the shoulder end of the anchor.

Having thus described my invention in a particular embodiment I am aware that numerous and extensive departures may be made therefrom but without departing from the spirit of my invention.

I claim:

1. A one-piece rail anchor of generally 90 E-form, comprising an elongated intermediate tongue terminating in a pair of oppositely extending retaining flanges, a pair of outer tongues disposed in spaced relation to the first tongue, and forming in connection therewith, a pair of rail flange embracing hooks, said hooks terminating at their ends in contacting portions engageable with a rail fillet uniting a side of the rail web with the rail base, said anchor adapted to be driven on to a rail flange by its hooked end and to be retained thereon by engagement of one of said flanges with the opposite lateral edge of the rail over which it is adapted to be snapped when the anchor 95 is driven to resiliently deflect said hooked end portion.

2. A one-piece rail anchor of generally 100 E-form comprising an elongated intermediate tongue adapted to underlie a rail base, 105 said tongue having a pair of oppositely disposed terminal flanges, and a pair of outer tongues disposed on either side of the intermediate tongue and in spaced parallel relation thereto, said anchor engageable with the rail by an end portion of one of said other tongues and with the fillet interconnecting the rail web and rail base, one of said terminal flanges engaging an opposite lateral edge portion of the rail base, said tongue end and flange being so spaced relative to the size of the rail as to resiliently 110 be spread apart upon placement of the anchor on the rail as aforesaid.

3. A one-piece rail anchor of generally 115 E-form comprising an elongated intermediate tongue adapted to underlie a rail base, 120 said tongue having a pair of oppositely disposed terminal flanges, and a pair of outer tongues disposed on either side of the inter-

mediate tongue and in spaced parallel relation thereto, said anchor engageable with the rail by an end portion of one of said other tongues and with the fillet interconnecting the rail web and rail base, one of 5 said terminal flanges engaging an opposite lateral edge portion of the rail base, said tongue end and flange being so spaced relative to the size of the rail as to resiliently be spread apart upon placement of the anchor 10 on the rail as aforesaid, said anchor invertible to secure it to a rail of a different size, one of said other tongues having its end spaced differently from its associated 15 said flange than the other tongue and flange cooperating therewith.

4. A rail anchor of generally T-form having a stem tongue terminating in a pair of oppositely extending flanges and its arms bent inwardly on opposite sides of the tongue 20 each alternatively engageable with the fillet connecting a rail web and base of rails of different sizes, each of said flanges adapted to cooperate with a corresponding one of 25 said arms to retain the anchor on a rail base by engagement with a lateral surface portion of the opposite rail base flange.

5. A rail anchor generally of T-form with the arms inturned toward the end of the 30 stem, said stem end being enlarged to provide flanges, said arms being engageable by their inturned top portions with the fillet of a rail, and to resiliently clamp the anchor on the rail, said stem portion underlying 35 the rail base and terminal flange for the stem engageable with the lateral surface of the rail base to resiliently retain the anchor thereon.

6. A rail anchor generally of T-form with the arms inturned toward the end of the 40 stem, said stem end being enlarged to provide flanges, said arms being engageable by their inturned top portions with the fillet of a rail, and to resiliently clamp the anchor on the rail, said stem portion underlying 45 the rail base and the terminal flange of the stem engageable with the lateral surface of the rail base to resiliently retain the anchor thereon, said other arm pendant 50 from the anchor below the rail and engageable by its lateral surface with a rail supporting tie to prevent creepage of the anchor.

7. A rail anchor of generally T-form having a stem tongue terminating in a pair of 55 oppositely extending flanges and its arms bent inwardly on opposite sides of the tongue each alternatively engageable with the fillet connecting a rail web and bases of rails of 60 different sizes, each of said flanges adapted to cooperate with a corresponding one of said arms to retain the anchor on a rail base by engagement with a lateral surface portion of the opposite rail base flange, the fillet 65 engaging ends of the arms being widened to

make the arms of approximately T-form, the pendant one of said arms engaging by a lateral surface of the T-head end with a rail tie to effect a canting and sluing effort on the anchor to simultaneously grip the rail 70 base by the combined canting and sluing movements effected on the rail base and fillet engaging anchor portions.

In testimony whereof I hereunto affix my signature this 7th day of January, 1929.

ALBERT F. FIFIELD.
